GAME BOARD

Everett L. Dreyer, Lincolnwood, Ill.

Application January 5, 1952, Serial No. 17,956

Term of patent 14 years

(Cl. D34—5)

To all whom it may concern:

Be it known that I, Everett L. Dreyer, a citizen of the United States of America, and a resident of Lincolnwood, in the county of Cook and State of Illinois, have invented a new, original, and ornamental Design for a Game Board, of which the following is a specification, reference being had to the accompanying drawings, forming a part thereof, and in which:

Fig. 1 is a plan view of a game board, showing my new design; and

Fig. 2 is an edge view thereof.

The essential features of my design are shown in full lines.

I claim:

The ornamental design for a game board, as shown and described.

EVERETT L. DREYER.
